SHARPENER FOR SAFETY RAZOR BLADES

William F. Whitman, Enterprise, Oreg.

Application November 27, 1935, Serial No. 51,914

1 Claim. (Cl. 51—153)

The invention relates to a sharpener for safety razor blades and more especially to a device for sharpening and stropping razor blades and other edge tools.

5 The primary object of the invention is the provision of a device of this character, wherein the blade or blades will be caused to automatically move into sharpening position with respect to a strop or sharpening slab and on reciprocation of 10 a carriage the said blades can be sharpened and honed with dispatch.

Another object of the invention is the provision 15 of a device of this character, wherein the cutting edges of safety razor blades will be held in proper relation to a strop or sharpening slab and such blades manually reciprocated for sharpening of the edges thereof, the blades being automatically reversed under reciprocation and maintained in close contact with the strop or slab to assure the sharpening and honing of the same.

20 A further object of the invention is the provision 25 of a device of this character, wherein the construction thereof is novel in form and is susceptible of accommodating different styles of safety razor blades so that the same can be acted upon for stropping and honing thereof, the device being adaptable to accommodate hollowed razor blades.

25 A still further object of the invention is the provision 30 of a device of this character, which is simple in construction, readily and easily operated, thoroughly reliable and efficient in its operation, durable and inexpensive to manufacture.

35 With these and other objects in view, the invention 40 consists in the features of construction, combination and arrangement of parts as will be hereinafter more fully described, illustrated in the accompanying drawing, which discloses the preferred embodiment of the invention and pointed out in the claim hereunto appended.

45 In the accompanying drawing:

Figure 1 is a fragmentary top plan view of a device constructed in accordance with the invention.

45 Figure 2 is a side elevation thereof.

Figure 3 is a sectional view on the line 3—3 of Figure 2 looking in the direction of the arrows.

Figure 4 is a plan view of a blade clamp or clip for use in the device.

50 Similar reference characters indicate corresponding parts throughout the several views in the drawing.

55 Referring to the drawing in detail, particularly Figures 1 to 3 inclusive, the device comprises a carriage which includes sides 10, top 11 and bot-

tom 12, preferably formed from metal and unitary with each other. Midway of the carriage and protruding from the top and bottom 11 and 12 at opposite sides 10 thereof are suitable bearing ears 13 for the journal ends 14 of axles 15 and 5 carried by these axles at one journal end 14 of each is a pinion 16, it being fixed thereto in any suitable manner. These pinions 16 are next to one side 10 of the carriage and mesh with an intermediate gear 17 journaled on a stud axle 18 10 fixedly held in the carriage.

Adapted to be disposed between the axles 15 and extended through the carriage is a honing strop, a portion thereof being indicated at 19, which at one face thereof has a sharpening slab 15 or surface 20 of any suitable abrasive or sharpening material or composition. At opposite edges of the strop 19 are binding strips 21 of metal, a flange 22, one of which has formed therein a perforated gear engaging track or rack 23 with which meshes a spur gear 24 made fast upon one of the journals 14 of an axle 15 so that upon reciprocation of the carriage upon the strop 19 reverse rotary motion will be imparted to said axles 15 for a purpose presently described.

Carried by the axles 15 are reversely set carriers 25 and 25', respectively, for razor blades or razor blade holders, one holder being indicated at 26 in Figure 4 of the drawing. These carriers at the heels thereof are formed with pintle sleeves 30 27 which are spaced apart and frictionally embrace the companion axles 15 while between the sleeves and active upon the axles 15 are coiled springs 28, these snugly embracing the said axles and each terminal 29 thereof anchored against 35 the carrier 25 next thereto. Thus on reverse movements of the carriage the carriers 25 and 25' will be reversely swung through the action of the gear and the spur gear tracking the rack 23 so that a razor blade 30 or the holder 26 therefor 40 when within each carrier will be properly positioned to have contact of its cutting edge with the strop 19 and the slab 20 for the stropping and sharpening operation on reciprocation of the said carrier.

45 The carriage at the side 10 opposite the gear 17 and midway of said carriage carries a handle 31 for the manual reciprocation of said carriage.

In the stropping and sharpening operation the carriage is moved to and fro or is reciprocated on the strop 19 by means of the handle 31. By this movement the blade carriers 25 and 25' are rocked to bring the blades 30 therein into contact with the strop 19, these carriers at opposite sides of the carriage being reversely rocked so 50 55

that honing and sharpening of the blades can be had as the carriers automatically operate simultaneously for presenting blades at opposite sides of the strop in position for honing and sharpening under reciprocation of the carriage.

The springs 28 frictionally binding against the axles 15 will afford a pressure on the carriers 25 and 25' so as to hold the cutting edges of the blades 30 in close contact with the strop 19 and the sharpening surface 20 thereof. The frictional engagement allows the positive turning of the carriers automatically on relation of the axle 15 and the free turning of the latter within a pintle sleeve 27 when the blades are in contact with the strop and surface 20 upon reciprocation of the carriage.

When it is desired to sharpen the razor blade the same is placed in the carrier next to the sur-

face 20 and for the stropping of such blade it is placed in the carrier 25' at the stropping side of the strop 19.

What is claimed is:

A stropping device comprising a carriage, a strop having a sharpening surface passed through the carriage, rocking razor blade carriers arranged at opposite sides of the carriage for presenting blades therein in reverse relation to each other to the strop and sharpening surface, respectively, turning axles journaled in the carriage and frictionally supporting the carriers, means on the strop and having gear connection with the axles for reversely turning the latter on reciprocation of said carriage, means for manually moving the carriage and friction springs included with the carriers and embracing the axles.

WILLIAM F. WHITMAN.
